June 1

4,097

de.

Patented June 28,

UNITED

ALBERT VA]

A

My invention relates to mortising machines in which a reciprocating motor with but two bearing is used and the object is to provide a mortising machine in which the motor is rotated by the mechanism illustrated in the accompanying drawing, in

causes
e 9 is t into
at the 45
th the hollow
ie 1.

chine, 50
ounted otor, a
n, the d by a
i spin-
free to stating e, with
n said
pindle,
n said
rossbar
55

achine,
ounted 65
otor, a
ocket, a
d bear-
sleeve,
id elec- 70
hollow
s of ad-
eans of
a dust
rossbar, 7
a bear-
id bear-
hollow
le from one end
ribed.
WARDS.